UNITED STATES PATENT OFFICE.

WILLIAM L. MERSFELDER AND ADOLPH F. RADKA, OF DETROIT, MICHIGAN, ASSIGNEES
TO DETROIT STOVE WORKS, OF DETROIT, MICHIGAN, A CORPORATION OF MICHIGAN.

MOLD FOR HOLLOW CASTINGS AND METHOD OF FORMING THE SAME.

1,266,700.

Specification of Letters Patent. Patented May 21, 1918.

Application filed July 23, 1917. Serial No. 182,171.

To all whom it may concern:

Be it known that we, WILLIAM L. MERSFELDER and ADOLPH F. RADKA, both citizens of the United States of America, both residing at Detroit, in the county of Wayne and State of Michigan, have invented certain new and useful Improvements in Molds for Hollow Castings and Methods of Forming the Same, of which the following is a specification, reference being had therein to the accompanying drawings.

The invention relates to the art of casting hollow articles and is more particularly designed for use in the forming of hollow cast rings for furnace construction. It is the object of the invention to avoid a large per cent. of loss in castings incident to the methods heretofore employed and also to simplify the method of forming the mold. To this end the invention comprises, first, the novel construction and method of forming the core, and further the method of assembling this core with the other parts of the mold, as hereinafter set forth.

In the drawings we have illustrated one specific construction of mold embodying our invention, in which—

Figure 1 is a plan view of the core mold;

Fig. 2 is a cross-section thereof;

30 Figs. 3, 4 and 5 are views similar to Fig. 2 showing successive steps in the forming of the core;

Fig. 6 is a cross-section showing the manner of forming the drag section of the mold;

35 Fig. 7 is a similar view showing the manner of forming the cheek section;

Fig. 8 is a similar view showing the manner of forming the cope section;

40 Fig. 9 is a section through the completed mold;

Figs. 10 and 11 are respectively a plan view and cross section through the castings formed in the mold.

45 Figs. 12 and 13 are views respectively showing a provision at the top of the core for resisting flotation stresses acting upon the core, and a supporting means for the core below the same.

The specific construction of casting illustrated in Figs. 10 and 11 is a hollow ring for use in furnace construction, comprising a central dome-shaped portion A, a surrounding hollow section B, a hollow radial connecting section C and a radial brace 55 member D diametrically opposite said hol-

low radial connecting section C. Usually such castings are formed in two sections flanged and bolted to each other, but where an integral construction is employed it is usual to cast the same by the use of a baked core. On account of the relatively large diameter of the hollow ring and slight thickness of the walls thereof it is difficult to successfully cast the member, as the contraction of the metal in cooling frequently causes fracture. As a result the percentage of loss of castings formed by this method is very high and the cost is therefore correspondingly great. With the present method this loss is almost entirely eliminated by the substitution of a yieldable green-sand core for the baked-core and by providing thorough ventilation for this core so as to permit escape of steam and gases. It is, however, necessary to provide some means of supporting the core within the outer mold, and a green-sand core is not sufficiently strong to be successfully supported from a limited bearing, as is the practice with baked cores. This difficulty is overcome by the employment of a supporting base for the core formed of baked sand, upon which the green-sand core is mounted and supported within the mold cavity. Provision is also made for reinforcing the green-sand core so that the upward stress due to the flotation of the molten metal may be successfully resisted.

In detail, the method of forming the mold is as follows: E is the core-box which is of cross-section corresponding to that of the ring B. In this box is first placed a series of chills or small metal plates F, which are distributed around the ring and conform to the cross-section of the lower portion of the box. Over these chills a perforated vent pipe is placed, this being formed in segments G G', etc., having their end formed for engagement with each other and at one point in the circle the pipe is connected with the radially, outwardly-extending pipe H. Metallic posts or stands I are then placed upon the chills F, these being forked at I' to embrace the sections of the vent pipes G and G'. The upper ends of these posts have a flat bearing I² and if desired the posts may be held in relative position by segmental connecting braces J.

When the members F, G, I and J are in position within the core-box, as shown in

- Figs. 1 and 2, the green-sand is filled in, is tamped and struck-off flush with the faces of the enlarged bearing I^2 , as shown in Fig. 3. An annular baked sand core K is then placed in the upper portion of the core-box and the latter is reversed in position and then removed from the core. This will leave the green-sand core supported upon a baked sand base, as shown in Fig. 5.
- 10 In forming the outer mold the drag section L is first formed by a suitable pattern M , and anchors N are embedded therein so as to expose chill faces N' , preferably in positions of registration with the posts I .
- 15 The core O for the dome A is formed in the drag and the face O' thereof is complementary to the face E' of the core, which latter is formed by a wedge E^2 placed in the core-box to permit of draft therefrom.
- 20 The drag section is struck-off on the line I' , after which the cheek section P is placed in position and sand filled therein to surround the pattern, as indicated at P' . In the segmental spaces between the dome and the outer ring lifter plates Q are placed, these being connected with vertical rods R extending upward. Sand is then filled in to these segmental spaces and after striking off the cheek section on the line P^2 the cope section S is placed in position and sand filled therein to unite with the sand in the segmental spaces. The cope section is provided, as is usual, with cross-bars S' for holding the sand in suspension therein and rods T are placed across the bars S' so as to register with the posts or stands I of the core. The rods R each have their upper ends locked to the cross-bars S' by wedge members R' , after which the cope may be drawn off, the segmental plates Q supporting the depending sections thereof.
- 25 The sections are then separated, the pattern removed and the core placed upon the drag, being supported by chaplets U resting upon the chill lugs N' and engaging the baked sand portion K of the core. Chaplets V are also placed in contact with the chill plates F at the top of the core in position to bear against lugs T' on the bars S' when the cope is in position. Thus after the cheek section and cope section are placed upon the drag the core will be supported therein and will be securely anchored against any flotation pressure. This is due to the fact that the baked sand core K will resist the direct pressure of the molten metal in the mold cavity and from this section the stress will be transmitted through the posts or stands I to the chill plates F and from the latter through the chaplets V to the lugs T' on the bars S' . The vent pipe within the core is connected with a pipe W passing through the cheek section and the mold is then ready for use.
- 30 It will be understood that in the casting

of the metal the contraction of the same is permitted as the green-sand core is yieldable and the steam and gases evolved by the heat are freely vented through the perforated pipe sections G G' , etc., and connecting pipe W . As a consequence there is no stress exerted upon the walls of the casting tending to fracture the same, and as the chills in contact with the surface of the metal are of very small extent unequal cooling stresses are avoided. In removing the casting from the mold the sand of the core may be readily removed through the opening B' in the ring B , and the segments G G' , etc., of the vent pipe as well as the braces J and stands I can also be removed through this opening. If there are any portions of the mold cavity other than those in the cope which present down-facing surfaces these may be formed by baked sand sections, as indicated at X 85 and X' .

What we claim as our invention is:

1. The method of forming molds for hollow castings, comprising the molding of a core section of green-sand, placing a complementary baked core section on top of said green-sand section, reversing, and removing from the core box and inserting in the cavity of the mold while supported on the baked section.

2. A core for hollow castings, comprising a baked base section, a green-sand section supported on and complementary to said base section, and rigid reinforcements embedded in the green-sand section for carrying stresses therethrough.

3. A core for hollow castings, comprising a baked base section, a green-sand section supported upon and complementary to said baked base section, and vertical posts or stands embedded in said green-sand section resting upon said baked section and carrying stresses therefrom upward to the top of the core.

4. A core for hollow castings, comprising a baked base section, a green-sand section supported upon and complementary to said baked section, a post or stand resting on said baked section and embedded in said green-sand section, and a chill forming a portion of the molding face resting on said post.

5. A core for hollow castings, comprising a baked base section, a green-sand section supported upon and complementary to said baked section, a post resting upon said baked section embedding in said green-sand section, a vent pipe in said green-sand section carried by said post, and a chill supported on the upper end of said post forming a portion of the molding face.

6. A mold for casting hollow articles, comprising a drag section and a cope section forming portions of the mold cavity therein, a core having a baked base portion and a

- complementary green-sand portion supported thereon, a post embedded in the green-sand portion and supported on the baked section, a chill at the upper end of said post forming a portion of the molding face, anchors in the drag and cope sections, and chaplets between said anchors and the core for carrying stresses thereinto and through said posts.
- 10 7. A mold for hollow castings, comprising a drag section, a cheek section and a cope section having formed therein complementary portions of the mold cavity, the drag and cope sections having anchors embedded therein and a core having a baked base sec-
- tion, a green-sand section supported upon and complementary thereto, a post embedded in said green-sand section, a vent pipe embedded in the green-sand section positioned by said post, a chill at the upper end of said post forming a portion of the molding face, chaplets for supporting the core upon the anchors in the drag section, and chaplets between said chill and anchor in the cope section for resisting the flotation stress exerted upon the core.
- 15 In testimony whereof we affix our signatures.

WILLIAM L. MERSFELDER.
ADOLPH F. RADKA.
